UNITED STATES PATENT OFFICE.

ARTHUR P. COTTLE, OF THREE RIVERS, MICHIGAN, ASSIGNOR TO SHEFFIELD CAR COMPANY, OF THREE RIVERS, MICHIGAN.

INTERNAL-COMBUSTION ENGINE.

1,117,642.

Specification of Letters Patent. Patented Nov. 17, 1914.

Application filed June 25, 1914. Serial No. 847,278.

To all whom it may concern:

Be it known that I, ARTHUR P. COTTLE, a citizen of the United States, residing at Three Rivers, Michigan, have invented certain new and useful improvements in Internal-Combustion Engines, of which the following is a specification.

This invention relates to improvements in internal combustion engines.

The main objects of this invention are: First, to provide in an internal combustion engine of the two cycle type an improved fuel feed means. Second, to provide in an internal combustion engine an improved fuel feed means in which a pump proper, float valves, and all moving parts except a check valve are dispensed with.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Fig. I is a side elevation of a two cycle engine embodying the features of my invention, the cylinder and crank case being shown in vertical central section. Fig. II is a detail vertical section through the carburetor and fuel feed mechanism on a line corresponding to line 2-2 of Fig. III. Fig. III is a horizontal section on a line corresponding to line 3-3 of Fig. II. Fig. IV is a detail vertical section on a line corresponding to line 4-4 of Fig. III. Fig. V is a detail vertical section on a line corresponding to line 5-5 of Fig. II. Fig. VI is a detail vertical section of a modified form of my invention. Fig. VII is a detail vertical section of another modified form of my invention.

In the drawing similar reference characters refer to similar parts throughout the several views, and the sectional views are taken looking in the direction of the little arrows at the ends of the section lines.

Referring to the drawing, I have shown my improvements embodied in a two-cycle engine as I have especially designed and adapted them to that type of engine. The

cylinder 1 is mounted upon the crank case 2 which in the structure illustrated, constitutes the compression chamber. The crank case opens into the cylinder so that the piston 3 serves as a pump plunger, as is well understood in two-cycle engine practice. The cylinder 1 is provided with a discharge or exhaust port 4 and with an inlet port 5. The inlet port 6 of the compression chamber in the structure illustrated is disposed so that it is open when the piston is at the end of its out stroke. The inlet port 6 is provided with a throttle valve 7. The compression chamber is connected to the cylinder by the delivery passage 8. The passage 8 is, for convenience in manufacture, formed in two members or sections 9 and 10. The delivery passage 8 is provided with a restriction 11 whereby the velocity and pressure of the air is varied during the delivery of the air to the cylinder. This restriction 11 within the passage 8 is, in effect, a "Venturi tube" restriction of the passage. The restriction 11 preferably converges as shown, as I find that form highly satisfactory and as it does not choke the passage or cause undesirable eddies therein. The fuel feed receptacle 12 is, in the structure shown, formed or cast integrally with the passage member or section 10. The fuel feed passage 13 leads from the bottom of the feed receptacle 12 to the delivery passage 8 opening into the delivery passage at the throat or delivery 14 of the restriction 11 and in the high velocity and low pressure zone of the delivery passage.

To accommodate the nozzle of the delivery passage 13 a boss-like portion is provided above the throat 14. See Figs. II and V. A regulating valve 17 is provided for the feed passage 13, the valve being shown as a needle valve, its threaded shank 18 being threaded into the plug 19 which is threaded into the boss 20 on the side of the delivery passage section 10.

The fuel receptacle 12 is provided with a cover 21 which closes it to atmospheric air, that is, it is closed against atmospheric air pressure. The fuel receptacle is connected by the fuel supply pipe 22 to the fuel storage reservoir 23 which, in the structure illustrated, is in the base of the engine. The supply pipe 22 is provided with a check valve 24.

A return pipe 25 is provided. This re-

turn pipe is connected to deliver to the reservoir 23. The fuel feed receptacle is connected by the passage 26, which opens into the feed receptacle above the mouth of the return pipe 25, to the passage 8 in front of the restriction 11 thereof. This passage 26 is always open into the high pressure and low velocity zone of the delivery passage. In the embodiment shown in detail in Fig. 10 II the return pipe is provided with a curved neck 25' so that it must face downward.

The fuel is drawn into the feed receptacle by the suction or inspiration impulses in the compression chamber which are transmitted 15 to the feed receptacle and the surplus is discharged therefrom on the compression impulses and forced into the return pipe 25. The diameter or capacity of this return pipe is such as to substantially retard the passage 20 of the fuel or air therethrough and is such that it does not, to an objectionable degree, affect the compression. The return check 24 prevents the return of the fuel to the reservoir through the feed pipe 22 on the 25 compression stroke, but any surplus is driven back to the reservoir through the return pipe 25. As stated, the diameter or the capacity of the return pipe is such that the surplus fuel does not flow freely therethrough as a 30 pipe of such diameter would materially affect the operating of the engine, but by providing a discharge properly restricted, the surplus fuel is delivered from the feed receptacle without materially affecting the 35 compression or the feeding of the fuel.

The pressure on the compression stroke is sufficient to force the surplus fuel into the return pipe,—on the suction stroke the weight of the fuel in the pipe acts against 40 the suction so that only part of the fuel is drawn back into the feed receptacle from the return pipe, but additional fuel is drawn thereto through the fuel pipe. Stated in another way, when the engine is running the fuel will surge back and forth in the return pipe but as the weight of the fuel is added to the out-surge and subtracted from the in-surge the motion of the fuel in the return pipe will be greater in the direction away 45 from the feed chamber, with the result that the surplus fuel will be discharged through the return pipe. As a float valve is entirely dispensed with the objections incident to such valves are eliminated.

50 On the charging stroke of the engine the air is compressed in the compression chamber, the passage 8 and the fuel receptacle. The piston itself acting as a valve, in the structure illustrated, prevents its escape 55 through the port 5 into the cylinder. When the inlet port 5 is uncovered the air is driven through the passage 8 and port 5 into the cylinder.

The velocity of air in the passage 8 as it 55 passes the restriction 11 increases and the

fuel is delivered by the combined inspirational action at the mouth of the feed passage and variations of pressure at this point and within the fuel feed chamber, which is, as stated, connected to the passage 8 within the high pressure low velocity zone thereof. As the passage 26 is relatively small a slight trapping action of the air within the fuel chamber is obtained. By this arrangement of parts I secure a structure in which fuel, 75 such as kerosene or the heavier hydrocarbons, may be used satisfactorily, and one in which there are no moving parts in the feed mechanism to become disarranged or worn out. The return pipe 25 is also preferably 80 of considerable length so that should any hot gas be forced therethrough it is sufficiently cooled so as to prevent danger of explosion within the fuel receptacle.

In the modification shown in Fig. VI a 35 restricted port or discharge 27 opens into a receptacle 28 which is provided with a drain 29. The structure previously described is, however, preferred by me as with the structure shown in Fig. VI there is a probability 90 of air being discharged in considerable quantities with the liquid and drawn back again on the suction and this would detract somewhat from the efficiency of the engine.

In the modification shown in Fig. VII 95 the curved neck of the return pipe is omitted. This form is quite satisfactory, but the curved neck prevents the possibility of the air funneling through the liquid to the mouth of the return pipe instead of forcing 100 the liquid into the pipe on the compression stroke.

The receptacle 28 might be dispensed with, but as some fuel would be discharged in vaporized form there would be an incident fire risk. With the parts thus arranged as I have illustrated and described, I secure a structure in which the proper relative proportions of air and liquid fuel are maintained through varying running conditions, 110 such as variations in speed, load and throttle opening.

My improved feed mechanism is very simple and economical in structure and, as stated, there are no movable parts to wear 115 out or become disarranged. I have shown my improvements particularly adapted to a two cycle internal combustion engine as that is the form in which I have embodied the same in practice. My improvements may be 120 embodied in four cycle or other type of engines.

Certain features of the structure illustrated and described in this application are described and claimed by me in my co-pending 125 application for Letters Patent Serial No. 839919, filed May 20, 1914.

I have not attempted to illustrate or describe such an embodiment or the various 130 embodiments which I contemplate as being

possible, as I believe the disclosure made will enable these skilled in the art to which my invention relates to adapt or embody the same as may be desired. I desire, however, 5 to be understood as claiming my improvements specifically in the form illustrated as well as broadly within the scope of the appended claims.

Having thus described my invention, what 10 I claim as new and desire to secure by Letters Patent, is:

1. The combination with an internal combustion engine having a combustion chamber and a compression chamber, of a delivery passage connecting said compression chamber to the inlet port of said combustion chamber, said passage having a restriction therein whereby the pressure and velocity of the air is varied during delivery, a fuel 15 feed receptacle closed to atmospheric air pressure, a feed passage delivering into said delivery passage within its high velocity low pressure zone, a fuel supply reservoir, a fuel supply pipe connecting said feed receptacle with said fuel reservoir, said feed receptacle being in a plane above the fuel reservoir, a check valve for said supply pipe, a fuel return pipe connected to said fuel reservoir, and an open passage communicating with said fuel feed receptacle above 20 the said return pipe and with said delivery passage within its high pressure and low velocity zone, the diameter of said return pipe being such as to substantially retard the 25 passage of the fuel therethrough, all coacting substantially as described.

2. The combination with an internal combustion engine, having a combustion chamber and a compression chamber, of a delivery passage connecting said compression chamber to the inlet port of said combustion chamber, said passage having a restriction therein whereby the pressure and velocity of the air is varied during delivery, a fuel 40 feed receptacle closed to atmospheric air pressure, a feed passage delivering into said delivery passage within its high velocity low pressure zone, a fuel supply reservoir, a fuel supply pipe connecting said feed receptacle with said fuel reservoir, a check valve for said supply pipe, a fuel return passage connected to said fuel reservoir and with said feed receptacle, and an open passage communicating with said fuel feed receptacle above the mouth of said return passage and with said delivery passage within its high pressure and low velocity zone, the capacity of said return passage being such as to substantially retard the passage of the 50 fuel therethrough, all coacting substantially as described.

3. The combination with an internal combustion engine having a combustion chamber and a compression chamber, of a delivery passage connecting said compression

chamber to the inlet port of said combustion chamber, said passage having a restriction therein whereby the pressure and velocity of the air is varied during delivery, a fuel feed receptacle, a feed passage delivering 70 into said delivery passage within its high velocity low pressure zone, a fuel supply reservoir, a fuel supply pipe connecting said feed receptacle with said fuel reservoir, a check valve for said supply pipe, a surplus 75 fuel discharge for said feed receptacle, and an open passage communicating with said fuel feed receptacle above the said discharge thereof and with said delivery passage within its high pressure and low velocity zone, the capacity of said surplus fuel discharge being such as to substantially restrict the 80 passage of the fuel therethrough, all coacting substantially as and for the purpose specified.

4. The combination with an internal combustion engine having a combustion chamber and a compression chamber, of a fuel feed receptacle, a fuel feed connection for said feed receptacle to the engine, a fuel 85 supply reservoir, a fuel supply pipe connecting said feed receptacle with said fuel reservoir, a check valve for said supply pipe, a fuel return pipe connected to said fuel reservoir, and a passage communicating with said compression chamber and with said fuel feed receptacle above the mouth of said return pipe whereby the fuel feed receptacle is subject to the alternate pressures and vacuums of the compression chamber, the capacity of 90 said return pipe being such as to substantially retard the discharge of the fuel therethrough, all coacting substantially as described for the purpose specified.

5. The combination with an internal combustion engine having a combustion chamber and a compression chamber, of a fuel feed receptacle, a fuel feed connection for said feed receptacle to the engine, a fuel supply reservoir, a fuel supply pipe connecting said feed receptacle with said fuel reservoir, a check valve for said supply pipe, a fuel return passage connected to said fuel reservoir and with said feed receptacle, and a passage communicating with said compression chamber and with said fuel feed receptacle above the mouth of said return passage whereby the fuel feed receptacle is subject to the alternate pressures and vacuums of the compression chamber, a capacity of 105 said return passage being such as to substantially retard the passage of the fuel therethrough, all coacting substantially as described for the purpose specified.

6. The combination with an internal combustion engine having a combustion chamber and a compression chamber, of a fuel feed receptacle, a fuel feed connection for said feed receptacle to the engine, a fuel supply reservoir, a fuel supply pipe connect-

ing said feed receptacle with said fuel reservoir, a check valve for said supply pipe, a surplus fuel discharge for said receptacle, and a passage communicating with said compression chamber and with said fuel feed receptacle above the said surplus fuel discharge thereof, whereby the fuel feed receptacle is subject to the alternate pressures and vacuums of the compression chamber, the capacity of the said surplus fuel discharge being such as to substantially restrict the discharge of fuel or gas therethrough, all coacting substantially as and for the purpose specified.

7. The combination with an internal combustion engine having a combustion chamber and a compression chamber, of a fuel feed receptacle, a fuel feed connection for said feed receptacle to the engine, a fuel supply reservoir, a fuel supply pipe connecting said feed receptacle with said fuel reservoir, a check valve for said supply pipe, a fuel return pipe connected to said fuel reservoir and provided with a curved neck whereby the mouth of the pipe faces downwardly, and a passage communicating with said compression chamber and with said fuel feed receptacle above the mouth of said return pipe whereby the fuel feed receptacle is subject to the alternate pressures and vacuums of the compression chamber, the

capacity of said return pipe being such as to substantially retard the discharge of the fuel therethrough, all coacting substantially as described for the purpose specified.

8. The combination with an internal combustion engine having a combustion chamber and a compression chamber, of a fuel feed receptacle, a fuel feed connection for said feed receptacle to the engine, a fuel supply reservoir, a fuel supply pipe connecting said feed receptacle with said fuel reservoir, a check valve for said supply pipe, a fuel return pipe connected to said fuel reservoir and having a downwardly facing mouth, and a passage communicating with said compression chamber and with said fuel feed receptacle above the mouth of said return pipe whereby the fuel feed receptacle is subject to the alternate pressures and vacuums of the compression chamber, the capacity of said return pipe being such as to substantially retard the discharge of the fuel therethrough, all coacting substantially as described for the purpose specified.

In witness whereof, I have hereunto set my hand and seal in the presence of two witnesses.

ARTHUR P. COTTLE.
